UNITED STATES PATENT OFFICE
2,512,557

This application is a continuation-in-part of my copending application Serial No. 259,088, filed March 1, 1939, now Patent No. 2,351,965, and is directed to the same subject matter, and is entitled "Fuel Injection Nozzle".

Robert K. Weldy, Detroit, Mich., assignor to Ex-Cell-O Corporation, Detroit, Mich., a corporation of Michigan
Application February 24, 1944, Serial No. 523,697
3 Claims. (Cl. 299—107.6)

The present invention relates to improvements in nozzles adapted particularly for delivering timed metered injections of liquid fuel in connection with the operation of internal combustion engines.

One of the objects of the present invention is to provide a novel fuel injection nozzle of the pintle type which comprises a minimum number of parts and which is simple and inexpensive in construction.

Another object is to provide a new and improved fuel injection nozzle having downflow passages adapted to cause the fuel to discharge from the nozzle tip in the form of a thin flat spray.

A further object is to provide a novel fuel injection nozzle comprising a one-piece body or casing and having novel means for limiting the height of rise of the pintle.

Other objects and advantages will become apparent as the description proceeds.

In the accompanying drawings:

Fig. 1 is a longitudinal axial sectional view of a fuel injection nozzle embodying the features of my invention.

Fig. 2 is a fragmentary axial sectional view of the nozzle tip on an enlarged scale.

Fig. 3 is a fragmentary end view of the construction shown in Fig. 2.

Fig. 4 is a fragmentary axial sectional view taken along line 4—4 of Fig. 2.

Fig. 5 is a fragmentary transverse sectional view taken along line 5—5 of Fig. 2.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring more particularly to the drawings, the fuel injection nozzle constituting the exemplary embodiment of my invention is of the general type disclosed in a copending application by James F. Hoffer, Serial No. 259,088, filed March 1, 1939, Patent No. 2,351,965, having an outwardly opening valve adapted to open and close with a popping action.

The nozzle comprises a body 1 adapted to contain all of the operating parts, and to be removably mounted as a replaceable unit in a suitable holder 2 partially shown in dotted outline (Fig.

Fig. 2 is a fragmentary axial sectional view of the nozzle tip on an enlarged scale.

Fig. 3 is a fragmentary end view of the construction shown in Fig. 2.

Fig. 4 is a fragmentary axial sectional view taken along line 4—4 of Fig. 2.

Fig. 5 is a fragmentary transverse sectional view taken along line 5—5 of Fig. 2.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring more particularly to the drawings, the fuel injection nozzle constituting the exemplary embodiment of my invention is of the general type disclosed in a copending application by James F. Hoffer, Serial No. 259,088, filed March 1, 1939, Patent No. 2,351,965, having an outwardly opening valve adapted to open and close with a popping action.

The nozzle comprises a body 1 adapted to contain all of the operating parts, and to be removably mounted as a replaceable unit in a suitable holder 2 partially shown in dotted outline (Fig.

end of the valve stem 15. More particularly, the hanger 17 consists of an elongated guide sleeve slidable in the bore section 6°, and having intermediate its ends an inner transverse wall 19 formed with a slot 20 in interlocking engagement with the head 18.

The valve 10 has an effective opening pressure area which is exposed to the pressure of the fuel within the chamber 6, and which is substantially equal to the area circumscribed by the stationary annular valve seat 12. When the valve 10 is in closed position, the flow of fuel to the discharge bore 7 for injection is blocked, and the hanger sleeve 17 is spaced inwardly from the annular shoulder 9. When the pressure of the fuel acting on the opening pressure area is sufficient to overcome the closing force of the spring 16, the valve member 13 is lifted outwardly from the seat 12 to open the valve 10 and start injection. The maximum height of rise of the valve member 13 is limited by engagement of the hanger sleeve 17 with the fixed stop shoulder 9.

A spray control pintle 21 is formed integral with and projects outwardly from the valve member 13. The pintle 21 extends slidably through the discharge bore 7, and coacts with the outer end thereof to define an annular discharge orifice 22. The pintle 21 is formed with a narrow cylindrical land area 23, and conveniently termed a pintle land, of full pintle diameter, at the extreme outer end, and a control cone 24 tapering inwardly therefrom. When the valve 10 is closed, the pintle 21 is fully retracted, and the pintle land 23 is located entirely within the bore 7. Upon opening movement of the valve 10, the pintle 21 is projected out of the body 1, and the control cone 24, in moving across the outer peripheral end edge of the bore 7, provides an injection orifice 22 of progressively increasing area. Inwardly of the tapered control cone 24, the pintle 21 is generally cylindrical in form, and in guiding surface engagement with the bore 7. As more fully explained in the aforesaid application, this popping action is obtained because the effective transverse area of the pintle 21, exposed to the pressure of the fuel when the valve 10 is open, is larger than the valve opening pressure area.

The nozzle body 1 is provided with suitable means for directing fuel during injection from the valve 10 to the discharge orifice 22 in such a manner that the issuing spray will be comparatively wide and thin and flat. A spray of this shape is desirable for certain types of combustion chambers not requiring sprays of high penetration, such for example as a flat chamber directly over the top of the engine piston. Sprays of this shape are also well adapted for engines of the electric ignition type, or engines in which the fuel is injected into air of low density.

In the preferred form, the means providing for the downflow of fuel from the valve comprises an internal peripheral groove 25 formed in the discharge bore 7 adjacent the valve inlet passage 11. The inner edge of the groove 25 is suitably beveled or chamfered to provide the fixed valve seat 12. Two inclined bores 26 are formed in the body 1 in diametrically opposed relation to provide downflow passages from the groove 25 along the pintle 21 to the discharge orifice 22. The bores 26 converge outwardly and at their inner ends intersect and communicate with the groove 25 and at their outer ends intersect and open to the discharge bore 7 adjacent the outlet end.

In operation, the two streams of fuel flowing through the passages 26 impinge upon each other after issuing from and just outside the discharge orifice 22. This impingement results in a wide fuel spray which is thin and flat in a plane intermediate the passages 26 and perpendicular to the plane of said passages.

The single-piece body is advantageous in that it provides a simplified and inexpensive construction requiring a minimum number of nozzle parts and reducing the difficulty and cost of manufacture. The construction is such that all the body forms and contours can be readily machined. In forming the body, the bores 6 and 7 are drilled from opposite ends. Then by access through the bore 6, the inner end of the bore 7 is flared to form the valve passage 11. The groove 25 is turned internally and by access through the discharge bore 7, the valve seat 12 is formed. Finally, the two converging bores or passages 26 are drilled from the discharge end of the nozzle.

I claim as my invention:

1. In a fuel injection nozzle, in combination, a body having an inlet passage opening to one end of said body and communicating with an axially aligned discharge bore opening to the other end of said body, said body being formed to provide an internal peripheral groove adjacent the inner end of said bore and a pair of down-flow passages disposed at opposite sides of said bore communicating at their inner ends with said groove and converging outwardly and intersecting said bore adjacent its outer end, a movable valve member controlling the flow of fuel from said inlet passage to said groove, and a pintle movable with said valve member and extending through said bore and having a peripheral surface of reduced diameter coacting with the inner surface of the outer end portion of said bore to define therewith an annular discharge orifice when said pintle is moved outwardly, said pintle having an inwardly tapering control cone portion extending across the outer ends of said inclined passages and providing communication between said passages and said orifice.

2. In a fuel injection nozzle, in combination, a body having an inlet passage opening to one end of said body and communicating with an axially aligned discharge bore opening to the other end of said body, said body being formed to provide a peripheral groove adjacent the inner end of said bore, an annular valve seat formed on said body at the inner internal edge of said groove, a valve member slidably disposed within said bore for co-operation with said seat to control the flow of fuel from said inlet passage to said groove, means for directing the fuel from said groove to said bore including a pair of passages disposed at opposite sides of said bore and inclined with respect to the axis of said bore and communicating at their inner ends with said groove and converging outwardly and intersecting said bore adjacent its outer end, and a pintle extending through said bore movable with said valve member and having a conical portion cooperating with the surface of the outer end portion of said bore to define therewith an annular outlet orifice when said pintle is moved outwardly and providing a flow passage between the outer ends of said inclined passages and said orifice.

3. In a fuel injection nozzle, in combination, a body having an inlet passage opening at one end, a discharge bore axially aligned with said passage and opening at the other end of said body, an inwardly flared passage connecting said inlet pas-

sage and said bore, said body additionally being formed with an internal peripheral groove in said discharge bore and located adjacent and outwardly of said flared passage, an annular valve seat formed on said body at the inner internal edge of said groove, a movable valve member mounted for movement into and out of cooperative engagement with said seat and coacting with said seat for controlling the flow of fuel through said flared passage to said groove, said valve member having a guide portion slidably in said bore, a pintle movable with said valve member in said bore and arranged to cooperate with the surface of the outer end portion of said bore to define an annular outlet orifice therewith when said pintle is moved outwardly, and a pair of passages disposed at opposite sides of said bore and inclined with respect to the axis of said bore for directing the flow of fuel to said orifice, said passages communicating at their inner ends with said groove and converging outwardly and intersecting said bore between the guide portion of said valve member and the outer end of said bore.

ROBERT K. WELDY.
